COMBINED CLOCK AND PLANTER

Frank D. Carter, Jr., San Leandro, Calif.

Application October 30, 1953, Serial No. 27,400

Term of patent 3½ years

(Cl. D42—7)

To all whom it may concern:

Be it known that I, Frank D. Carter, Jr., a citizen of the United States and a resident of San Leandro, county of Alameda, California, have invented a new, original, and ornamental Design for a Combined Clock and Planter, of which the following is a specification, reference being had to the accompanying drawing, forming a part thereof.

Figure 1 is a front perspective view of a combined clock and planter, showing my new design;

Figure 2 is a rear elevational view thereof; and

Figure 3 is a top plan view thereof.

The dominant characteristics of my design reside in the portions shown in full lines.

I claim:

The ornamental design for a combined clock and planter, substantially as shown and described.
